SETTLED SOLIDS REMOVING APPARATUS

Edward S. Wiard, Englewood, Colo.

Application December 27, 1933, Serial No. 704,126

5 Claims. (Cl. 210—55)

This invention relates to the art of separating solids from liquids and has as an object the provision of means operable in combination with settling or thickening tanks for the removal of the solids concentrated in said tanks.

A further object of the invention is to provide improved apparatus readily adaptable to settling or thickening tanks of various types, sizes and shapes for the efficient removal of the solids concentrated in said tanks.

A further object of the invention is to provide improved solids-removing apparatus operable in combination with settling and thickening tanks with a minimum of disturbance and agitation of the solids concentrated in said tanks.

A further object of the invention is to provide improved solids-removing apparatus operable in combination with settling and thickening tanks and susceptible of adjustment of its operating elements through a wide speed range to adapt said apparatus to the requirements of a specific installation.

A further object of the invention is to provide an improved solids-removing unit readily adaptable to existing settling and thickening tank installations.

A further object of the invention is to provide an improved solids-removing unit that is simple of manufacture and installation, efficient and substantially automatic in operation, durable in use and free of onerous maintenance requirements.

My invention consists in the construction, arrangement and combination of elements hereinabove set forth, pointed out in my claims and illustrated by the accompanying drawings, in which:—

Figure 1 is a side elevation of a portion of a conventionalized settling or thickening tank where-with is operatively combined a typical embodiment of the invention, a portion of the tank being broken away to better illustrate the assembly. Figure 2 is a plan view of the showing of Figure 1. Figure 3 is a plan view, on an enlarged scale, of a typical solids collector employed in the invention. Figure 4 is a vertical section, on the same scale as Figure 3, axially of the collector assembly and one form of its mounting.

In the construction of the improvement as shown, the numeral 10 designates a conventional settling or thickening tank such as is commonly employed in various arts for the gravity concentration of finely divided solids in a liquid vehicle, the portion of the tank 10 illustrated being but typical of any suitable shape and construction and including circular as well as the generally

preferred and more efficient rectangular forms. In practice, the mixture to be acted upon is fed to the tank slowly and in such manner as to set up a minimum of disturbance in the tank and clear liquid, from which the solids have separated, is discharged from the tank at a point necessarily remote from the feed, the solids of the mixture being gravity concentrated in a relatively dense layer on the floor of the tank. It is obvious that where very finely divided solids are to be settled a tank or series of tanks must be provided having a very large capacity in proportion to the rate of feed.

Since the invention comprises a unit arranged for travel relative to the tank 10, suitable means are provided for supporting the unit for travel in a plane parallel with the floor of said tank, such means being illustrated in this instance as a rigid, two-rail track 11 positioned immediately above and parallel with one side of said tank and suitably fixed with the upper margins of the rails in a common plane parallel with that of the tank floor. Mounted above and to travel along the rails 11, a wheeled platform 12, of any suitable construction and arrangement, is provided to act as the base of the solids-removing unit. Any suitable means may be provided for driving the platform 12 relative to its support, the arrangement illustrated comprising a variable speed electric motor 13 fixed to the platform 12 and suitably connected to derive its operative energy from an overhead power line 14 through a pole and contact assembly 15 carried by said platform, the motor 13 being provided with a worm or similar gear 16 on its driven shaft in operative engagement with a gear 17 fixed to one of the axles of the platform 12, so that, when the motor 13 is operated the platform is caused to travel along the track 11, the variable speed character of the motor 13 and the gear relation between said motor and the platform 12 permitting infinite adjustment of the rate of travel imparted to the platform 12.

Mounted for rotation about its axis in suitable bearings carried by the platform 12, a shaft 18 depends vertically from said platform within the tank 10 and carries on its lower end a solids collector thus positioned in close proximity with the tank floor. The solids collector, designated generally by the numeral 19, may take any one of several forms having substantially identical functions, but preferably is of the type illustrated in detail in Figures 3 and 4 wherein a base plate 20 is fixed to and in perpendicular relation with the shaft 18 and supports a vertical rib 21 rising therefrom and arranged thereon to present

a convolute spiral closing at its inner end against the shaft 18, which arrangement provides a convolute passage on the upper surface of the plate 20 leading from the outer margin thereof inwardly to the shaft 18, so that, when the collector 19 is rotated in the proper direction, solids engaged thereby will be led by said convolute passage from outer margins of the collector inwardly of the latter to the shaft 18. To rotate the shaft 18 and collector 19 an independent power unit is preferably employed, such a unit being illustrated as a variable speed electric motor 22 carried by the platform 12 and provided with a worm or similar gear 23 on its driven shaft operatively engaging a gear 24 fixed to the upper end of the shaft 18, the variable speed character of the motor 22 and its gear relation with the shaft 18 permitting adjustment of the rotative speed of the collector 19 independently of the rate of travel of the platform 12. The motor 22 preferably is operatively connected with the pole and contact assembly 15 so as to derive its operative energy from the power line 14.

The solids gathered by the collector 19 are preferably elevated for discharge from the tank 10 by suction means carried by the platform 12, one such means being illustrated as comprising a suitable suction pump 25 carried by the platform 12 in driven relation with a variable speed electric motor 26 which latter derives its operative energy from the power line 14 through the pole and contact assembly 15, the outlet 27 of the pump 25 discharging into a launder 28 whereby the collected solids may be gravity fed to the desired location. Various means may be employed for operatively connecting the inlet of the pump 25 with the area of maximum solids concentration adjacent the junction of the shaft 18 and collector 19, one such means being illustrated in Figures 3 and 4 by means of dotted lines and comprising a simple conduit communicating at one end with the pump inlet and having its other end open and positioned, by means of fittings engaging the shaft 18, adjacent the junction of the shaft 18 and collector 19. It is more efficient and conducive of less disturbance of the settled solids within the tank 10 to withdraw the solids gathered by the collector 19 through the shaft 18, which may, of course, be accomplished in various ways, one construction effective to this end being shown in detail in Figure 4. In this latter figure, the shaft 18 is shown as formed with an internal bore communicating at its lower end through a port 29 with the innermost convolution of the collector 19. That portion of the shaft 18 immediately below the platform 12 is slotted or otherwise apertured and rotates within an annular chamber or housing 30 fixed to said platform and with which a conduit 31 leading from the inlet of the pump 25 communicates, so that suction effect deriving from said pump acts through the conduit 31, chamber 30, shaft 18 and port 29 to lift the solids gathered by the collector 19 for discharge through said pump into the launder 28.

In the practical use of the apparatus illustrated and described, the particular operative installation and arrangement will necessarily depend upon the requirements of the art and equipment concerned. In some installations, the platform 12 will be arranged, by means of automatic reversing switches, to repetitiously traverse the same section of track 11 from one side of a tank 75 to the other side, a plurality of track installa-

tions, each equipped with a solids-removing unit, being employed to cover the area of the tank floor. With circular tanks, a concentric series of tracks may be employed with a plurality of the solids-removing units, or a spiral track may be 5 equipped with a single unit arranged for reverse travel or other return to the initial point. Likewise, a single unit may be arranged to travel entirely about a rectangular tank, if desired, or, instead of reversing for back travel on a single 10 straight track, means may be provided whereby the unit is raised out of the tank and returned to its initial point for repetitious action.

Where the solids-removing units are employed in multiple in a single tank to travel along paths 15 parallel with the feed of said tank, said units may act as classifiers, since the heavier and coarser particles of the solid matter will settle nearest the feed side of the tank and the finer particles nearest the discharge side thereof, so that the 20 unit nearest the feed side will deliver coarser solids and the other units will deliver progressively finer solids as their paths are progressively nearer the discharge side of said tank.

It is to be noted that because of the relatively 25 slow travel of the platform 12 and the relatively slow rotation of the collector 19, very little disturbance of the settled solids is had, and that, by virtue of the adjustments provided, the speeds of travel and rotation, as well as the pump speed, 30 may be proportioned to give maximum solids recovery with a minimum of disturbance and agitation.

It will be readily apparent that the instant invention, when compared with sweeps, rakes and 35 similar mechanical appliances now commonly employed for the same purpose, presents obvious advantages in respect of efficiency, installation and maintenance costs and adaptability, besides permitting the use of tanks of a size to which 40 the previous appliances could not be successfully adapted.

Since many changes in the specific form, construction and arrangement of the elements 45 shown and described may be had without departing from the spirit of the invention, and may in fact be required in adapting the principle of the invention to specific installations and uses, I wish to be understood as being limited solely by the scope of the appended claims, rather than 50 by and details of the illustrative showing and foregoing description.

I claim as my invention—

1. The combination with a settling tank of a 55 solids-removing unit arranged for travel relative to said tank, said unit including a suction element, a rotatable gathering element operatively associated with said suction element, and means in said gathering element operable through simultaneous rotation and translation of the latter to 60 concentrate solids from the floor of said tank about and adjacent the intake of said suction element.

2. The combination with a settling tank of a 65 solids-removing unit arranged for travel relative to said tank, said unit including a suction element disposed with its intake adjacent the floor of said tank, rotatable gathering means operatively associated with said suction element, and a spiral channel in said gathering means operable through simultaneous rotation and translation of the latter to concentrate solids from 70 the floor of said tank about and adjacent the intake of said suction element.

3. The combination with a settling tank of a 75

solids-removing unit arranged for travel relative to said tank, said unit including a suction element disposed with its intake adjacent the floor of said tank, rotatable gathering means operatively associated with said suction element for translation therewith, said gathering means including a plate closely adjacent and coplanar with the floor of said tank, and a spiral channel on said plate operable through simultaneous rotation and translation to concentrate solids from the floor of said tank on said plate about and adjacent the intake of said suction element.

4. The combination with a settling tank of a solids-removing unit arranged for travel relative to said tank, said unit including a suction element carriage-disposed for translation with its intake adjacent the floor of said tank, power means operable to translate said carriage relative to said tank, rotatable gathering means operatively associated with said suction element for translation therewith in constant advancing engagement

against solids settled in said tank, independent power means operable to rotate said gathering means, and elements in said gathering means operable through simultaneous rotation and translation of the latter to concentrate settled solids about and adjacent the intake of said suction element.

5. The combination with a settling tank of a solids-removing unit arranged for travel relative to said tank, said unit including a suction element disposed with its intake adjacent the floor of said tank, gathering means carried by said suction element for translation therewith in constant advancing engagement with solids settled in said tank, means for rotating said gathering means, and a spiral channel included in said gathering means and operable through rotation thereof to concentrate settled solids about and adjacent the intake of said suction element.
